UNITED STATES PATENT OFFICE.

ELMER J. MANNING, OF JANEVILLE, WISCONSIN.

CARBURETER.

1,310,426.

Specification of Letters Patent. Patented July 22, 1919.

Application filed December 26, 1914. Serial No. 878,993.

To all whom it may concern:

Be it known that I, ELMER J. MANNING, a citizen of the United States, residing at Janesville, county of Rock, and State of Wisconsin, have invented new and useful Improvements in Carbureters, of which the following is a specification.

The object of my invention is to provide means for reatomizing the liquid which tends to accumulate in the pipe or manifold between the main carbureting or mixing chamber. It is well known that quantities of liquid hydrocarbon or of condensed hydrocarbon, or even of water carried by the hydrocarbon, tend to collect along the suction pipe or manifold of the engine under certain conditions and gradually accumulate at the lower end in sufficient quantity to seriously interfere at times with the proper action of the carbureter. My invention contemplates collecting such liquid in an auxiliary receiver provided with means for atomizing such liquid, preferably during the intervals when the throttle valve is wholly or partially closed.

In the drawings—

Figure 1 is a side elevation of one form of carbureter embodying my invention.

Fig. 2 is a detail sectional view, drawn on line $x-x$ of Fig. 1.

Fig. 3 is a detail view of the auxiliary atomizer as seen from the inner end.

Fig. 4 is a side view of another form of carbureter embodying my invention in a modified form suited to the requirements of the carbureter to which it is applied.

Fig. 5 is a detail sectional view of the modified atomizer employed in the carbureter shown in Fig. 4.

Fig. 6 is a view of the same as seen from the inner end.

Like parts are identified by the same reference characters throughout the several views.

The carbureter shown in Fig. 1 is provided with an ordinary float chamber A, an air inlet at B communicating with a carbureting passage C, into which extends a fuel nozzle D, the carbureting passage leading to an outlet duct or pipe E. A throttle valve is located at F and operated by means of a valve lever G. All of these parts may be of any ordinary type and require no detailed description.

The pipe E is adapted to communicate with the cylinder of the engine or with a

manifold connection to a set of cylinders. Near its lower end this pipe is provided with an interior shoulder H, having a channel I at its upper surface. Immediately below the shoulder H, a plug J is threaded into an aperture in the pipe E. This plug J is hollow, being provided with a cavity J' into which liquid collecting in the channel I may flow through a vertical channel I'. A nozzle tube L extends into the plug from its inner end, and the extremity of the tube within the plug is bent downwardly, as shown at L'. This nozzle tube is open at both ends and the downwardly bent extremity therefore constitutes an inlet for the nozzle, when suction is applied at the other end to withdraw liquid from the cavity J'.

An air blast tube M extends inwardly through the plug from its outer end, and the inner extremity is bent upwardly at M' to a position adapted to direct the blast of air across the inner end of the nozzle tube L. The outer end of the tube M communicates with the external atmosphere, and the hollow plug J with the nozzle tube L and blast tube M, constitute an atomizer adapted for operation when a partial vacuum exists in the pipe E. This atomizer may operate to some extent under ordinary conditions, but its effectiveness will be greatly increased whenever the throttle valve at F is closed or nearly closed. In such case, a nearly complete vacuum will be created in the pipe E and an effective blast of air will therefore be delivered through the blast tube M. The air blast crosses the inner extremity of the nozzle tube L and therefore not only increases the suction through said nozzle tube, but also breaks up or atomizes the stream of discharging liquid.

With the construction above described, all liquid accumulating or condensing upon the walls of the pipe E above the shoulder H, may be collected in the channel I and delivered to the reservoir plug or plug cavity J', from which it will be discharged and re-atomized as above described. It sometimes happens, however, that quantities of liquid will accumulate in the lower portion of the passage C, either by reason of condensation or on account of a too rapid discharge of liquid hydrocarbon through the fuel nozzle D. I therefore provide a suction duct N in the form of a by pass duct leading from the lower part of the passage C upwardly to the plug cavity J'. This by pass duct or

pipe N, therefore, affords a means of communication across the throttle valve F, so that when the throttle valve is closed or nearly closed, the suction of the engine piston will be extended through the by pass and exerted upon the liquid in the lower part of the passage C, withdrawing the liquid from such passage and delivering it through the atomizer nozzle L. In this manner the surplus liquid in the carbureter or its connecting ducts may be withdrawn, atomized and delivered to the engine while the latter is throttled. The quantity being small and the quantity of air being also small, a combustible mixture will be obtained, which will be delivered to the engine cylinder as a small combustible charge. When the engine is running, liquid hydrocarbon may accumulate in the lower portion of passage C and held therein by the incoming air, entering through the fitting B, whether the passage C is partially obstructed at its inlet end or not. The inrushing currents of air are of such force as to retain the hydrocarbon in the substantially horizontal portion of the passage C, the amount thus retained being, of course, limited. But the amount of liquid which runs down into this portion of the passage is also limited, and occurring almost entirely when the engine is first throttled, and before the flow of hydrocarbon has adjusted itself to the throttled condition. It is well understood that when the engine is running rapidly the flow of hydrocarbon is substantially continuous, and this causes an excess discharge immediately following the closing movement of the throttle valve. This discharge will be caught by the strong suction exerted through the pipe N, and drawn upwardly through said pipe, as above explained.

My invention, in the form illustrated in Figs. 1, 2 and 3, is adapted to be applied to a carbureter having a vertically extending outlet, or a conducting pipe which extends upwardly from the throttle valve casing. It frequently happens, however, that this pipe or duct extends in a substantially horizontal direction from the carbureter or from the throttle valve casing, as is the case with the pipe e illustrated in connection with the carbureter shown in Fig. 4. In this carbureter, the parts corresponding with those shown in Fig. 1, are given the same reference letters with the exception that small case letters are employed for the re-atomizing device.

In this construction, an auxiliary atomizer, comprising a hollow plug j is employed. This plug is adapted to be screwed verti-

cally into an aperture formed in the underside of the pipe e, the cavity j' constituting a cup shaped cavity or depression in the bottom of the pipe e into which liquid may flow. In this auxiliary atomizer, l is the nozzle through which the liquid is discharged from the bottom of the cup, and the pipe m is the air blast pipe corresponding with the pipe M in Fig. 1 and similarly discharging across the discharge end of the nozzle l. Owing to the fact that the plug extends vertically, it is not necessary that the pipe l should be bent or elbowed at the extremity within the cavity j', since the lower end of the nozzle l will be immersed in the liquid whenever the latter accumulates to any considerable depth. The operation of this atomizer is the same as that illustrated in Fig. 1, but it is not necessary to provide a by pass around the throttle valve, for the reason that in this type of carbureters any liquid accumulating in the air passages will flow to and be received in the cavity j' of the atomizer plug.

I claim—

1. A carbureter, including a receiver for condensed liquid, in combination with a nozzle tube, an air blast tube adapted to direct a blast of air across the outlet of the nozzle tube, said nozzle tube having its inlet end in the lower part of said receiver, and a by pass tube leading to said receiver, said receiver being adapted for connection with the charging duct of an internal combustion engine and said by pass tube being adapted to connect said receiver with said charging duct at a point distant from the receiver, said receiver being adapted to receive liquid hydrocarbon from different points in said charging duct but on opposite sides of a throttle valve therein, substantially as described.

2. The combination with a carbureter, of a valved outlet duct adapted to communicate between the carbureter and the cylinder of an internal combustion engine, independent means for delivering liquid collecting in said outlet duct between the carbureter and the valve to a point in said duct beyond the valve, and means for atomizing the liquid so delivered, said atomizing means being also adapted to atomize liquid collecting in said duct on the side of the valve opposite that occupied by the carbureter.

In testimony whereof I affix my signature in the presence of two witnesses:

ELMER J. MANNING.
